UNITED STATES PATENT OFFICE.

JOHN SISTEK AND JAMES SPINKA, OF CHICAGO, ILLINOIS.

FLUID-ACTUATED VISE.

941,543.

Specification of Letters Patent. Patented Nov. 30, 1909.

Application filed April 14, 1909. Serial No. 489,939.

To all whom it may concern:

Be it known that we, JOHN SISTEK and JAMES SPINKA, citizens of the United States, and residents of the city of Chicago, county 5 of Cook, and State of Illinois, have invented new and useful Improvements in Fluid-Actuated Vises, of which the following is a specification.

Our invention relates to vises operated 10 by fluid pressure.

The object of our invention is to provide a vise of the character mentioned which will be quick-acting and thoroughly efficient in its operation and one which will be strong 15 and durable and comparatively simple of construction.

Other objects will appear hereinafter.

With these objects in view our invention consists in a vise characterized as above mentioned and in certain details of construction and arrangement of parts all as will be hereinafter fully described and particularly pointed out in the claims.

Our invention will be more readily understood by reference to the accompanying drawings forming a part of this specification, and in which,

Figure 1 is a sectional side elevation of the preferred form of embodiment of our invention, and Fig. 2 is a vertical transverse section taken on line $x-x$ of Fig. 1.

Referring now to the drawings 1 indicates the fixed jaw of our vise the same being suitably secured, preferably by bolts 2 passing 35 through the flanged base 3 thereof and nuts 4 threaded upon said bolts, to the work-bench or any other suitable support 5. Having its horizontally extending preferably rectangularly formed shank 6 slidably resting 40 in the base portion 3 of the jaw 1, such portion acting as a guide therefor and preventing rotary movement thereof, is a movable vise jaw 7 adapted to coact with the jaw 1. Said jaws are preferably provided with 45 coacting pipe jaws or grips 8 detachably secured therein by means of removable pins 9. Secured as by bolts 10 and nuts 11 threaded upon said bolts to the top surface of the support 5 directly beneath the jaw 1 is a 50 plate 12. The base 13 of the jaw 7 is in sliding dove-tailed connection with said plate, as clearly shown in Fig. 2, thereby adapting the latter to prevent all relative lateral movement of said jaw other than in 55 a longitudinal direction.

Secured as by bolts 14 and nuts 15 thread-

ed upon said bolts to the under side of the support 5, the longitudinal axis thereof being in vertical alinement with the line of movement of the vise jaw 7 is a cylinder 16 60 in which is mounted the piston 17 carried upon the extremity of the piston rod 18. Interposed between the rearward side of said piston and the rear head 19 of the cylinder 16, the latter being formed with a reduced 65 portion or housing 20 for the reception thereof, is a helical compression spring 21 adapted to normally hold the piston 17 in a position at the forward extremity of said cylinder. 70

22 indicates a rocker arm mounted at substantially its center upon a pin 23 for oscillatory movement in a slot 24 provided in the support 5 adjacent the jaw 7 and rearward extremity of the cylinder 16 in alinement 75 with the line of movement of the former and the axis of the latter. Longitudinally extending through the jaw 7 and shank 6 thereof, the same being rigidly secured thereto by reason of its enlarged preferably 80 squared head 25 abutting the outward end surface of said jaw and a nut 26 threaded upon the opposite extremity thereof in engagement with the outward extremity of said shank is a member 27. 28 and 29 indicate 85 similar links, the same respectively connecting the bifurcated head 25 of the member 27 and the upper extremity of the arm 22, and the bifurcated exteriorly projecting extremity of the piston rod 18 and the lower 90 extremity of the arm 22. By such provision it is evident that any movement of the piston 17 will cause the simultaneous movement or actuation of the jaw 7.

With the end in view of effecting the actuation or reciprocation of said piston by means of fluid pressure, we provide a three-way valve 30 of any ordinary or preferred design, the same being preferably positioned upon the support 5 adjacent the left-hand 95 extremity of the vise. Connected to said valve is a pipe 31 extending through the forward head 16' of the cylinder 16 and establishing communication between the former and the forward end of said cylinder, a pipe 100 32 which communicates with any suitable supply of air, water, gas or other fluid under pressure, and an exhaust pipe 33. 34 indicates the operating lever or handle of said valve, the latter being so designed that when 105 said handle is in a position at one extremity of its movement or in a position as shown in

full line in Fig. 1, communication will be established between the supply pipe 32 and the pipe 31 and hence the forward end of the cylinder 16, and when in a position at the 5 other extremity of its movement or in a position as shown in dotted lines in said figure, communication will be established between said cylinder and the exhaust pipe 33. Hence by such provision upon turning the handle 10 34 to one position, the piston will be forced to the left against the tension of the spring 21 obviously causing the movement to the right of the jaw 7 and hence the closing of the vise, the position of the removable parts 15 under such circumstances being shown in dotted lines in Fig. 1. Upon turning said handle to a position at the other extremity of its movement said piston will be returned to its initial position by the spring 21, hence 20 causing the return of the vise jaw 7 to its initial or opened position.

By the provision of a vise of a construction as shown and described, the provision of a fluid actuated vise of the highest possible efficiency both in construction and operation will be effected.

While we have shown what we deem to be the preferable form of our invention, we do not wish to be limited thereto as there might 30 be many changes made in the details of construction and arrangement of parts without departing from the spirit of our invention comprehended within the scope of the appended claims.

35 Having described our invention what we claim as new and desire to secure by Letters Patent is:

1. In a vise of the class described, the combination of a fixed jaw, a coacting movable jaw having a rectangular shank slideable in 40 said fixed jaw, a guide plate for said movable jaw in dove-tailed connection with the base thereof, a power cylinder mounted beneath said jaws having its axis disposed 45 parallel with the line of movement of said movable jaw, a piston and piston rod carried by said cylinder, a rocker arm mounted for oscillation in the vertical plane including the axis of said power cylinder, links 50 connecting the extremities of said rocker arm with said movable jaw and said piston

rod, whereby simultaneous movement of said jaw and said piston is effected, a pipe leading from one extremity of said power cylinder, a fluid supply pipe and an exhaust pipe, 55 a three-way valve connecting said pipes whereby communication may be established between said first named pipe and either said supply pipe or said exhaust pipe, and a compression spring provided in said cylinder 60 in engagement with said piston for normally holding said movable jaw in opened position, substantially as described.

2. In a vise of the class described, the combination of a fixed jaw, a coacting movable 65 jaw having a rectangular shank slideable in said fixed jaw, a guide plate for said movable jaw in dove-tailed connection with the base thereof, a power cylinder mounted beneath said jaws having its axis disposed 70 parallel with the line of movement of said movable jaw, the said cylinder being composed of a larger chamber constituting a piston chamber and a smaller chamber constituting a guide and socket for a compression 75 spring, a piston and piston rod carried by said cylinder, a rocker arm mounted for oscillation in the vertical plane including the axis of said power cylinder, links connecting extremities of said rocker arm with said 80 movable jaw and said piston rod, whereby simultaneous movement of said jaw and said piston is effected, a pipe leading from one extremity of said power cylinder, a fluid supply pipe and an exhaust pipe, a three-way valve connecting said pipes whereby 85 communication may be established between said first-named pipe and either said supply pipe or said exhaust pipe, and a compression spring provided in said cylinder in engagement with said piston and resting in 90 said socket for normally holding said movable jaw in opened position, substantially as described.

In testimony whereof we have signed our 95 names to this specification in the presence of two subscribing witnesses.

JOHN SISTEK.
JAMES SPINKA.
